[57] ABSTRACT

A structural frame capable of absorbing impact energy comprises structural frame member of metallic material defining closed rectangular cross-section. Portion of each of the structural frame members is bent in the direction perpendicular to the longitudinal direction of the frame and energy absorption materials of metallic material with bowl-shaped projections are attached to those two opposing inner surfaces of the frame members which oppose in the direction of bending so that the bowl-shaped projection abut against each other. Upon collision, due to the resistance to plastic deformation of the bowl-shaped deformation the shape of the cross section of the structural frame may be maintained in its initial state and no abrupt decrease of bending moment takes place.

STRUCTURAL FRAME CAPABLE OF ABSORBING IMPACT ENERGY

The present invention relates to an improvement in structural frame such as a side member of a frame for a car, and has its object to increase absorption efficiency of an impact energy upon collision or the like and to provide a small and light-weight structural frame while maintaining sufficient reliability and safety.

It has been suggested, in a structural frame such as a car frame or a side member, to flex a portion thereof to absorb impact energy. However, since such a frame has too rapid decrease of load for deformation stroke and low absorption efficiency for energy, the overall thickness of the structural frame must be increased for compensation therefor, which results in unnecessarily large and heavy structure in order to achieve requisite energy absorption efficiency.

The present invention is intended to provide a novel and improved structural frame which overcomes the above short comings.

The present invention will now be described in connection with the accompanying drawings in which:

FIG. 1 is a fragmentary plane view of a car frame in accordance with one preferred embodiment of the present invention,

FIG. 2 is a perspective view of one form of energy absorbing material,

FIG. 3 is a plane view, partly broken away, of a structural frame curved section,

FIG. 4 is a front view, partly broken away, of the structure of FIG. 3,

FIG. 5 is a cross-sectional view taken on a line V—V in FIG. 3,

FIG. 6 is a lateral cross-sectional view of a structural frame curved section having an energy absorbing material affixed, in accordance with another form of the present invention,

FIG. 7 is a perspective view of other form of energy absorbing material,

FIG. 8(A), (B) and (C) illustrate deformed conditions of the structural frame of the present invention,

FIG. 9(A), (B) AND (C) illustrates deformed condition of a conventional structural frame, and

FIG. 10 shows characteristic curve of axial load of the structural frame versus stroke.

Referring to the drawings, FIG. 1 is a plane view showing a front section of structural frames 1 and 2, which form side members of a car, to which the present invention is applied. The structural frames 1 and 2 made of steel defining closed rectangular shape in cross section, as shown in FIG. 5, are formed with curved sections 3 and 4, respectively, in the directions perpendicular to their respective longitudinal directions. These sections serve as energy absorption sections.

Several pairs of energy absorption materials 5 and 6 are arranged in the curved sections 3 and 4, as shown in FIGS. 2 through 5.

Each energy absorption material is made of steel or the like and has a bowl shaped projection 7a at its bottom, as shown in FIG. 2, and mounting flanges 8 and 9 at opposite sides of an opening and is shaped such that it is accommodated in the structural frames 1 and 2.

As shown in FIGS. 1, 3 and 5, the energy absorption materials 5 and 6 are attached to flanges 8 and 9, as

shown in FIG. 2, by means of welding or the like so that bowl-shaped projections 7a and 7b abut against those two inner sides 10 and 11 of the inner sides of the structural frames 1 and 2 which oppose in the direction of curvature.

While three pairs of energy absorption materials are shown in the illustrated embodiment it should be understood that the present invention is not limited to this. Also, while the energy absorption members 5 and 6 are curved such that the flanges 12 and 13 between the flanges 8 and 9 are slightly spaced from the inner sides 10 and 11 of the structural frames 1 and 2, the present invention is not limited to such a particular structure.

FIG. 6 shows another embodiment of the energy absorption materials in which bowl-shaped projection of each energy absorption material is of dual structure comprising an inner member 14 and an outer member 15. FIG. 7 shows other embodiment in which the bowl-shaped projection 7a shown in FIG. 2 is replaced with a flat projection 16 in which reinforcement grooves 17 and 18 are formed, and opposite sides of the flat projection 16 is formed into a box-like mount having side-walls 19 and 20, the bottom walls 21 and 22 thereof being adapted to be attached to the inner surfaces of the structural frames.

The impact energy absorption action of the structural frames thus constructed in accordance with the present invention is now described in comparison with a conventional structural frame. When the structural frames are used as the side members constituting car frames, the curved section 3 is formed, as stated above, to assure strength rigidity during run and to absorb impact energy. The curved section 3 shares with bending moment corresponding to the amount of eccentricity (H) shown in FIG. 1. Upon collision this section is bent to absorb the impact energy.

In a conventional structural frame 23, as shown in FIG. 9(A), at the initial stage of collision, that is, when an axial load (F) is applied, the structural frame 23 deforms as shown in FIG. 9(B) by 24, and the frame cross-section begins to collapse before full plastic collapse load of the structural frame 23 is reached. As the structural frame further deforms the shape of the cross-section is substantially collapsed, as shown in FIG. 9(C), until it no longer sustains bending moment. Thus, the axial load versus stroke characteristic curve in this case has, as shown in FIG. 10 by double dotted line, a peak of the axial load (F) at a point 9(B) which corresponds to the status of FIG. 9(B), and rapidly decreases thereafter, and at point 9(C) corresponding to the status of FIG. 9(C) the stroke proceeds without substantial resistance.

On the contrary, in the structural frame 25 according to the present invention as shown in FIG. 8(A), at the time when the axial load (F) is applied, the bowl-shaped projections 28 and 29 of the paired energy absorption materials 26 and 27 attached to the curved section are abutted against each other and begin plastic deformation. Due to the resistance to this plastic deformation the shape of the cross-section of the structural frame 25 is maintained substantially in its initial state so that it may withstand the load until the full plastic collapse load of the structural frame 25 is reached. When the stroke of the load further increases, the plastic deformation of the energy absorption materials 26 and 27 proceeds as shown in FIG. 8(C) and the cross-

sectional shape of the structural frame 25 deforms depending upon the amount of deformation so that no abrupt decrease of the bending moment takes place.

Accordingly, in the axial load versus stroke characteristic curve for this case, the axial load (F) does not fall after passing through the point 8(B) corresponding to the status of FIG. 8(B), as shown in FIG. 10 by a solid line, and reaches the point 8(C) corresponding to the status of FIG. 8(C) and does not exhibit abrupt decrease even thereafter.

This fact demonstrates that the structural frame according to the present invention presents a desirable impact energy absorption characteristic.

As has been illustrated and described, according to the present invention, the absorption efficiency of the impact energy upon collision can be increased and hence smaller and lighter structural frame may be provided for absorbing a given impact energy. By suitably adjusting and/or selecting the plate thickness of the structural frame, the shape of cross section, material, the amount of eccentricity of the curved section, or the shape of the energy absorption material, the thickness and material thereof, the axial load or deceleration may be controlled to any desired value. Furthermore, since the structural frame provides absorption and relaxation of the impact energy which are necessary and sufficient for the structural frame, it assures the reliability and the safety and also insures the safety of the passengers when it is applied to a car frame or the like.

What is claimed is:

1. In a strengthening frame for automobiles, a strengthening frame capable of absorbing impact energy comprising
a strengthening frame of metal having a closed cross-section such as rectangular shape;
a plurality of curved portions curved inwardly of the said strengthening frame by the front and/or rear

end of the said frame in its longitudinal direction; and

5 energy absorption members of metal, wherein the bottom is projected in a bowl-shape and the side edge portions of the opening function as flanges for the mounting,

10 the bowl-shaped projections of the said energy absorption members being attached to the inside of the said strengthening frames at their curved portions adjacent and opposite to each other.

15 2. A structural frame capable of absorbing impact energy in accordance with the claim 1 wherein the energy absorption material is a dual bowl-shaped projection consisting of an inner member and an outer member and mounting flanges at its opposite sides of the opening.

20 3. A structural frame capable of absorbing impact energy in accordance with the claim 1 wherein the energy absorption material has a flat projection at its bottom, reinforcement grooves being formed in said flat projection, a box-like mount having side walls being formed on opposite sides of the flat projection, and a mounting bottom wall at opposite side ends of the opening.

25 4. A structural frame capable of absorbing impact energy comprising structural frame members made of metal defining closed rectangular cross-section, a portion of each of said structural frame members being bent in the direction perpendicular to the longitudinal direction of the structural frame members, and energy

30 absorption materials made of the metal having bowl-shaped projections at its bottom and mounting flanges at its opposite sides of the opening to the projection which are attached to those two opposing inner surfaces of the structural frame which oppose in the direction of bending whereby the bowl-shaped projections 35 may abut against each other.
